UNITED STATES PATENT OFFICE.

RICHARD H. GOLDSBOROUGH, OF WASHINGTON, DISTRICT OF COLUMBIA.

TURBINE.

1,151,175.

Specification of Letters Patent. Patented Aug. 24, 1915.

Application filed February 1, 1913. Serial No. 745,715.

To all whom it may concern:

Be it known that I, RICHARD H. GOLDSBOROUGH, a citizen of the United States, residing at Washington, in the District of Columbia, have invented new and useful Improvements in Turbines, of which the following is a specification.

My invention relates to improvements in steam turbines and consists in the constructions, combinations and arrangements herein described.

The object of my invention is to provide a more efficient form of reversing chamber and exhaust ports for the steam turbine illustrated in United States Patent 953,013, issued March 22, 1910, in which I employed an open annular hollow U shaped core and exhaust ports leading out laterally from said core. In my present preferred construction 15 I dispense entirely with said core and arrange the exhaust ports in such manner that the exhaust steam passes out tangentially in the direction of its final flow from the rotor, thereby completely utilizing the residual velocity of said exhaust.

A further object of my invention is to provide an improved turbine having either full or part peripheral admission with exhaust at its vertical center, thereby accommodating the turbine to variations of load.

In the following drawings forming part of the application and in which similar reference symbols indicate corresponding parts in the several views, Figure 1 is a detail 35 axial section, illustrating one embodiment of my invention; Fig. 2 is an end elevation with the end plate removed, illustrating the stator reversing chamber in its relation to the rotor, and the peripheral steam chamber divided into sections; Fig. 3 is a perspective 40 view of the stator reversing chamber illustrated in Figs. 2, 5 and 6; Fig. 4 is a perspective view of the rotor; Fig. 5 is an enlarged detail view illustrating the stator 45 reversing chamber, juxta-placed nozzles and rotor; Fig. 6 is a perspective view of a portion of the rotor, stator reversing chamber and nozzle ring.

Referring to the drawings:—1 indicates a 50 rotor secured to a shaft 13, which extends through the heads 8 of a turbine casing 2. The periphery of the rotor is provided with a series of tangentially disposed U shaped buckets or deflecting surfaces 3, the division walls between the several buckets having a

portion 12 cut away forming an annular groove in the face of the rotor.

Fig. 3 indicates a stator reversing chamber of multi-cellular ring extending around the rotor 1, comprising a series of U shaped buckets 5 having their front and back enclosing walls inclined toward each other, and being provided with semicircular openings 6 forming in combination with the annular groove 12 on the rotor a continuous 60 annular open core. A nozzle ring 9 provided with juxta-placed nozzles 7, suitably inclined for directing the steam at an efficient angle to the rotor, is secured to the stator reversing chamber, Fig. 3, which is 65 also provided with suitable means for attaching it to the interior of the casing 2 in correct relation to the annular supply chamber 11.

In the operation of my invention, steam is 70 admitted to the supply chamber 11, from which it is directed by the annular series of juxta-placed nozzles 7 to the U shaped buckets 3 in the rotor 1. The steam upon leaving the nozzles converges and unites into an annular sheet before entering the buckets 3. This initial sheet or layer of steam is deflected and discharged, at a reduced velocity, from the U shaped buckets into the circumscribing multi-cellular stator reversing 75 chamber, Fig. 3. The steam thus discharged at reduced velocity from the rotor is directed by the stator reversing surfaces 5, to the rotor where it consolidates as a secondary layer with and is deflected by the initial 80 steam layer simultaneously directed to the rotor buckets 3; the more rapidly flowing initial layer constituting a fluid guide for efficiently deflecting such secondary steam layer. The initial and secondary steam layers are 85 discharged from the rotor to the circumscribing series of stator reversing surfaces 5, by which they are re-directed as consolidated 90 secondary and tertiary layers to the rotor; the initial steam layer simultaneously directed to the rotor buckets 3, constituting a fluid guide for efficiently deflecting such secondary layer—which latter acts in turn as a 95 fluid guide for the tertiary layer. The initial, secondary and tertiary steam layers are 100 discharged from the rotor to the circumscribing series of stator reversing surfaces 5, by which they are re-directed as consolidated 105 secondary, tertiary and quaternary layers to the rotor, where they consolidate with the 110

initial steam layer simultaneously directed thereto; the several concentric layers constituting the more slowly moving succeeding layers. After the four concentric layers, or 5 as many more as may be predetermined, have been thus deflected as a consolidated body in the rotor, the last layer passes out into the exhausting chamber 19, through the opening 6, in the direction of its final flow from the 10 rotor — being dynamically deflected therefrom by the adjacent layer of steam without the aid of any metallic guiding or deflecting means. The above described steps are repeated during the continuous operation of 15 my invention until all the actuating steam has been re-directed, by cyclonic inflow, a plurality of times to the rotor and finally exhausted at its vortical center.

In the above described operation, the actuating steam is directed to the several rotor surfaces 3, in a continuous tangential cyclonic inflow having the outer envelop composed of high velocity steam while the inner currents are of gradually decreasing velocity, 25 and finally exhausting by residual velocity at the center of gyration.

Having thus described my invention, what I claim as new and desire to secure by Letters Patent is:—

- 30 1. In a turbine, the combination of a rotor provided with deflecting surfaces, means for directing an inflowing body of steam to said surfaces, said means comprising a continuous series of convergently disposed nozzles, and an annular receiving and reversing multicellular ring, said ring provided with intercellular openings whereby said steam is exhausted at its vortical center in the direction of its final flow from said rotor.
- 40 2. In a turbine, the combination of a rotor provided with deflecting surfaces, means for directing steam currents to said rotor and a multicellular reversing chamber whereby the steam is caused to flow in a cyclonic course, 45 and intercellular spaces with openings therein to vortically exhaust therefrom said steam in the direction of its final flow.
- 50 3. In a turbine, the combination of a rotor provided with deflecting surfaces, means for directing an inflowing body of steam to said surfaces, said means comprising a continuous series of convergently disposed nozzles, and an annular receiving, reversing and separating multi-cellular ring, said ring 55 provided with an annular open vortex core whereby said steam is exhausted at its vor-

tical center in the direction of its final flow from said rotor.

4. In a turbine, the combination of a rotor provided with deflecting surfaces, means for directing a cyclonically inflowing mass of steam to said surfaces comprising steam nozzles and a multi-cellular reversing chamber having V shaped division walls between each cell, and openings in the middle of the apex 65 of each division wall, whereby said steam is exhausted at its vortical center.

5. In a steam turbine, the combination of a rotor provided with deflecting surfaces, means for directing initial steam currents to 70 said surfaces, a stator reversing element having a series of hollow V shaped partitions and exhaust ports comprising gaps in the outer edge of said partitions.

6. In a steam turbine, the combination of 75 a rotor, means for directing steam currents to said rotor, a stator reversing element comprising a series of U shaped deflecting surfaces, inclosing walls forming V shaped spaces between said deflecting surfaces and 80 exhaust ports comprising gaps in the edges of said walls opening into said spaces; said edges corresponding to the chord of said U shaped deflecting surfaces.

7. In a turbine, the combination of a rotor 85 provided with deflecting surfaces, means for directing an inflowing sheet of steam to said surfaces; said means comprising a continuous series of convergently disposed nozzles, and a multicellular receiving and reversing element provided with an open vortex core whereby said steam is exhausted by 90 vortical action in the direction of its final flow from said rotor.

8. In a turbine, the combination of a rotor 95 and stator provided with tangentially disposed buckets, means for directing a continuously touching series of currents to said buckets, and semi-circular gaps in the middle portion of the axially disposed edges of 100 the tangentially disposed walls of said buckets, said gaps constituting substantially a continuous exhaust opening.

In testimony whereof I have hereunto set my hand in the presence of two witnesses, at 105 Washington, District of Columbia, this 31st day of January 1913.

RICHARD H. GOLDSBOROUGH.

In presence of—

EDWARD M. WEEKS,
RICHARD C. MULLER.
